UNITED STATES PATENT OFFICE.

JOHN DAVIDSON, OF TUTBURY, BURTON, ENGLAND, ASSIGNOR TO THE RECORD CRUDE OIL ENGINE COMPANY, LIMITED, OF LONDON, ENGLAND.

INTERNAL-COMBUSTION ENGINE.

Application filed September 10, 1923. Serial No. 661,919.

To all whom it may concern:

Be it known that I, JOHN DAVIDSON, a British subject, residing at The Elms, Tutbury, Burton, England, have invented certain new and useful Improvements in Internal-Combustion Engines, of which the following is a specification.

Internal combustion engines have already been constructed in which two or more working pistons are connected with a charging piston, all three pistons reciprocating simultaneously in the same direction. I have found, however, that a design of engine of this type which is capable of performing satisfactory service when driven by an explosive mixture at low horsepower is subject to serious defect when more heavily built or adapted for use on the Diesel or semi-Diesel principle. On the one hand, the extreme accuracy of workmanship necessary to prevent binding of one or other of the pistons renders it very difficult to produce such engines on an industrial scale, and on the other hand even when the necessary accuracy has been obtained, the extent of distortion arising from unequal expansion between the hot working pistons and cylinders and the comparatively cool charging pistons and cylinders is such in the case of large engines as to render smooth and economical working very problematical.

The present invention has for its primary object to provide improvements whereby the above objections may be avoided in large engines and engines of the Diesel and semi-Diesel type constructed as above described.

The invention accordingly consists primarily in the arrangement wherein the working pistons are laterally movable relatively to the charging pistons. I find that this improvement is practically essential with all engines of the said type working on the Diesel or semi-Diesel principle and is of considerable value with larger engines of the ordinary explosive mixture type.

A further object of the present invention is to avoid a further difficulty met chiefly in engines of the Diesel or semi-Diesel type wherein the explosion chamber is required to be considerably less than in the case of explosive mixture engines. In engines of the type set forth, the explosive mixture has been led through ports in the wall of one working cylinder and out through ports in the wall of another working cylinder, so that

the whole of said mixture is required to pass through the narrow space between the roof of the explosion chamber and the top of the partition between the two cylinders. For the purpose of reducing the size of this space it is impracticable to raise the partition and piston-stroke beyond certain limits, as otherwise the flow of gas on inlet and exhaust is thereby seriously impeded, and the present invention accordingly consists in the construction whereby the top of each piston extends beyond the working face and thus beyond the partition between the two cylinders when at the top of its stroke. Preferably this is accomplished by providing a mutilated dome-shaped top, the dome corresponding in shape to the corresponding element of a curved surface constituting the roof of the explosion chamber but having a cut-away face at the side adjoining the aforesaid partition.

The invention is illustrated in the accompanying drawings in which Figs. 1 and 2 represent sectional views in plan and elevation and Fig. 3 a side view of an engine of the semi-Diesel type, Fig. 4 being a view of a detail. Fig. 5 is a sectional detail showing the manner of connecting the pistons to permit a relative tilting movement thereof.

The engine here illustrated comprises two units 1, 2 which each comprise a pump cylinder 3 and two charging cylinders 4, 5 rigid therewith arranged side by side above the pump cylinder. In each unit reciprocates a pump or charging piston 6 and two working pistons 7, 8 which are fixed to and reciprocate simultaneously in both directions with their respective charging pistons in known manner. From the position shown, as the pistons of unit 1 descend, air is sucked in through inlet 9 by the pump piston through the port 10 which has just been opened by the slide valve 11. As the pump descends the slide valve also descends for a time but afterwards rises again and closes the port 10 and, in its further movement, when the piston commences its return stroke, puts the port 10 into communication with the port 12 by means of the annular channel 13. Thus the charge of air which has been sucked into the left-hand pump chamber 3 is compressed and discharged into the chamber 14, Figs. 2 and 3, whence it is delivered, as the piston 7 descends, into

the inner working cylinder 4 of the unit 2 driving out the spent gases through the ports in the outer cylinder 5, and thereafter serving for the combustion of a charge of fuel in the unit 2 in the explosion chamber common to the two cylinders.

The pump piston 3 of the unit 2 works in corresponding manner to scavenge and charge the cylinders of unit 1, its port 15 being opened to inlet by ports 16 in the valve 11 on the rise of the latter and to the chamber 14 by the aforesaid channel 13 on the depression of the valve. Fuel is injected through the passage 17 and fired by the hot bulb 18, Fig. 3 all in known manner

Now according to the present invention the working pistons 7, 8 are mounted on the pump pistons 6 by means permitting relative movement thereof so that the said moving parts in heavy engines are capable of a certain amount of flexible adjustment to irregularities in the construction of the cylinders and/or distortion of the cylinders and pistons due to unequal expansion during working. In the form shown this is accomplished by providing the pistons 7, 8 with an inwardly-extending annular flange 19 adapted to be engaged by a flanged cap 20, Fig. 4, held down by a bolt 21 passing through the working face of the pump piston 6. In the form shown, the engaging surfaces of the pump piston 6 and the lower faces of the working pistons and caps are plane and transverse to the axis of the pistons so that relative movement is confined to a horizontal plane at right angles to the axis of the pistons.

It is to be understood, however, that I do not wish to be limited to movement in a horizontal plane as I may provide a slightly spherical or cylindrical surface of cleavage between the elements intended to be capable of relative movement so that a certain amount of tilting will be made possible for the pistons 7, 8, as shown in Fig. 5. Alternatively, the working pistons may be hingedly mounted on short connecting rods which are themselves hinged to the pump pistons.

It is further to be understood that said relative movement is in practice only required to be made possible within small limits, and that the bolts 21 in the form shown are intended to be tightly engaged to maintain the moving surfaces in true contact.

The engaging flange of the cap 20 is provided with two flats 20^a as shown in Fig. 4 to enable it to be inserted in the bottom of the piston.

It will be understood that in the above construction the air entering the cylinder 4 and exhausted through the cylinder 5 is required to pass through the space between the top of the partition 22 formed by the

cylinder walls, 4, 5 and the roof 23 of the common explosion chamber. On the one hand, for free movement of the air it is desirable that the distance between the partition 22 and roof 23 be considerable, but with Diesel and semi-Diesel engines it is desirable that the effective size of the explosion chamber be reduced to an extent conflicting with the aforesaid requirement, and the present invention further consists in the construction in engines of the above type having a plurality of working pistons, whereby the tops of said pistons are extended above the working faces and therefore above the top of the partition 22 so as to restrict the effective size of the explosion chamber without restricting the passage of the air when the pistons are withdrawn.

In the form shown, the roof 23 of the explosion chamber is formed to a concave surface with which the dome-shaped tops 24 of the pistons, 7, 8 are shaped to correspond. The said tops rise in height from the outer to the inner edges as viewed in Fig. 1 and there terminate in cut-away faces which face each other across the partition 22. The cut-away faces may be generally plane or cylindrical or I may if desired form concave spherical or like mutilations designed so as to give the desired restriction of the size of the explosion chamber.

Although the invention has been described with regard to an engine comprising two units, it is obviously applicable to an engine comprising one unit (in which case the underside of the pump piston would effect the scavenging) and to engines comprising multiple units. Where more than two working pistons are mounted on one pump piston, I prefer to employ an even number scavenged in pairs as above described so that the arrangement of the dome-shaped pistons would be applicable thereto without alteration. The movable mounting of the working piston is also applicable to engines having only one working piston mounted on an annular charging piston in each unit.

I claim:

1. In an internal combustion engine, a working piston, a charging piston connected therewith, a working cylinder, a charging cylinder rigid therewith, the working piston being mounted on the charging piston, by means permitting of a bodily movement of the charging piston over the face of the working piston in such a manner that the axis of the charging piston is laterally displaced.

2. In an internal combustion engine, a charging piston a charging cylinder, a plurality of working pistons connected to the charging piston, a plurality of working cylinders rigid with the charging cylinder and having a common explosion chamber, means

- whereby the working pistons are capable of lateral movement relatively to said charging piston in a plane transverse to the axes of said piston.
3. In an internal combustion engine, a charging piston a charging cylinder, a plurality of working pistons connected to the charging piston, a plurality of working cylinders rigid with the charging cylinder and having a common explosion chamber, means whereby the working pistons are capable of tilting movement relatively to said charging piston.
4. In an internal combustion engine, a charging piston, a charging cylinder, a pair of working pistons secured to said charging piston a pair of working cylinders rigid with said charging cylinder and having a common explosion chamber, means for the ingress of fluid into one of said working cylinder and means for the exhaust of fluid from the other of said working cylinders, said working pistons having tops extending upwardly beyond their working faces and above the partition formed by the adjacent walls of said working cylinders, when the pistons are in firing positions.
5. In an internal combustion engine, a charging piston, a charging cylinder, a pair of working pistons secured to said charging piston a pair of working cylinders rigid with said charging cylinder and having a common explosion chamber, means for the ingress of fluid into one of said working cylinders and means for the exhaust of fluid from the other of said working cylinders said working pistons having extended tops shaped to correspond with the shape of the roof of the explosion chamber, said tops having cut-away faces facing each other.
6. In an internal combustion engine, a charging cylinder, a plurality of working cylinders rigid therewith, a charging piston in the charging cylinder, a plurality of working pistons mounted on said charging piston and operating in the working cylinders, and means connecting the working pistons and charging piston to permit of a bodily movement of the working pistons over the face of the charging piston in a manner to permit lateral displacement of the axes of the working pistons.

In testimony whereof I affix my signature.

JOHN DAVIDSON.
